Application May 11, 1937, Serial No. 141,922
In Germany May 12, 1936

2 Claims. (Cl. 64—25)

The present invention relates to governing devices and has particular reference to governing devices specially applicable for the purpose of varying the timing of an engine driven auxiliary, such as a fuel injection pump, in response to variations in speed and operation of the engine.

The primary object of the invention is the provision of governing means of novel and improved form which is very accurately sensitive to variations in speed, which is simple and compact in form and readily applicable for incorporation in the line of drive to an engine auxiliary, and which will reliably effect very accurate relative rotation of a driven part with respect to a driving part in accordance with the speed of rotation of the parts, whereby to accurately control the timing with respect to the cycle of operation of an engine, of an auxiliary driven from the engine through the governing device.

Because of the special utility of the device forming the subject matter of the present invention as a governing means for timing the operation of an engine driven auxiliary, it will be hereinafter described in connection with its application as the means for governing the timing of a fuel pump of conventional form for injecting fuel to an internal combustion engine, but it will be understood that the invention is not limited in its use to this particular form of application.

For a better understanding of the more detailed nature of the invention and the advantages to be derived from its use, reference may best be had to the ensuing portion of this specification taken in conjunction with the accompanying drawing forming a part hereof.

In the drawing:

Fig. 1 is a side elevation of an engine equipped with a regulating device embodying the invention;

Fig. 2 is an enlarged view of the regulating mechanism taken approximately on the line 2—2 of Fig. 3; and

Fig. 3 is a section taken on the line 3—3 of Fig. 2.

Referring now more particularly to Fig. 1, the engine is designated generally at A and is of known kind in which fuel is injected into the engine cylinders during the later part of the compression stroke to form with air previously drawn into and being compressed within the cylinders a combustible mixture which is ignited at or near the end of the compression stroke by timed ignition means. In the engine shown, air for combustion is drawn into the inlet manifold 10, the quantity being controlled by the

throttle valve 12. Fuel is injected into the cylinders through suitable injectors 13 supplied by the fuel pump B. In the embodiment illustrated the quantity of fuel supplied per working stroke is automatically regulated through vacuum control apparatus 14 connected to the intake manifold by pipe 16 and responsive to changes in pressure in the intake manifold.

The fuel charges supplied to the engine are ignited in timed relation to the engine cycle by means of an electrical spark ignition system of conventional form indicated generally at C. The specific form of the fuel pump and the manner of its control with respect to the quantity of fuel supplied, form no part of the present invention and any suitable form of injection equipment and control thereof with respect to quantity of fuel supplied may be employed. Also, the specific type of ignition equipment employed is not germane to the present invention.

As shown in Fig. 1, drive for the fuel pump is provided by the drive shaft 18 appropriately geared to the engine crank shaft. Between shaft 18, which operates in fixed timed relation to the engine cycle, and the pump B there is interposed the governing mechanism D, which is connected to the fuel pump by shaft 20.

Referring now more particularly to Figs. 2 and 3, the governing mechanism D comprises a cup-shaped driven member 22 the hub portion 24 of which is fixed to shaft 18 by a key 26 and suitable lock-nut. The rim portion 28 is provided with internal gear segments 30a and 30b at diametrically opposed sides of the rim.

The driving member 32 is in the form of a double disc wheel having a hub portion 34 rotatably mounted on the hub 24 of the driven member 22 and spaced disc-like flanges 36 and 38. An annular closure member 40 fixed to the flange portion of member 22 and bearing against flange 38, forms in effect a part of member 22 which with member 32 provides a closed casing.

Member 32 may be connected to the drive shaft 18 in any suitable manner as by means of a dog clutch, the lugs of which are indicated at 42 in Fig. 3. Centrifugal weights 44 and 46 are pivotally mounted on bolts 48 and 50 respectively, between the flanges 36 and 38 of member 32. Weight 44 is provided with a spur gear segment 52a, the teeth of which mesh with the internal teeth 30a, and weight 46 is provided with a spur gear segment 52b, the teeth of which mesh with the internal teeth 30b.

As will be evident from Fig. 2, the centrifugal weights are generally fish shaped in form. The

5 pivot points provided by the bolts are located on the diameter or axis of symmetry passing through the centers of the spur gear sectors of the weights when the device is at rest and also, 10 as will be noted from the drawing, the pivot 5 points are located in the portions of the weights lying close to the central shaft of the device. The two weights, which are geometrically congruent, are joined reciprocally at their ends by 15 springs 54 and 56 in such manner that the spring 54 acts as the loading spring for the weight 44 and spring 56 acts as the loading spring for weight 46. The spring 54 is attached by means of a pin 58 to weight 46 at a point in the vicinity 20 of the pivot point provided by the bolt 50. At its opposite end spring 54 is connected by means of pin 60 to weight 44 at a place remote from the pivot point provided by the bolt 48. It will be evident from the drawing that movement of the pin 58, upon movement of weight 46, will be 25 relatively much less than movement of pin 60 upon equal movement of weight 44, due to the difference in the distance of these pins from their respective pivot points. Consequently, spring 54 may be considered as being anchored to weight 46 and providing spring load for weight 44.

30 Similarly, spring 56 is attached by means of pin 62 to weight 44 at a place relatively close to the pivot point 48 and is attached to weight 46 by pin 64 at a point remote from the pivot point 50. Weight 44 may thus be considered as providing anchorage for spring 56 which acts as the loading spring for the weight 46.

35 In Fig. 2 the weights are shown in their position of rest, being held in abutment against hub portion 34 of member 32 by the retracting action of the loading springs.

40 When member 32 is driven, the weights transmit the driving force through the gear teeth to the member 22 and shaft 20.

45 Under the influence of centrifugal force the weights 44 and 46 tend to move outwardly about their pivot points against the reaction of the loading springs, the extent to which the weights turn about their pivots being dependent upon the relation of the speed of rotation of the governor, and consequently the centrifugal force developed, and the strength of the loading springs.

50 Since the structure is symmetrical, the outward movement or deflection of each weight is always equal to that of the other. As will be evident from Fig. 2, outward movement of the weights will cause relative rotational displacement of member 22 with respect to member 32, through the action of the gear teeth.

55 If, for example, the direction of rotation of the shaft 18 and the governing device as a whole is as indicated by the arrow 66 in Fig. 2, displacement of the weights from the position shown in the figure will cause the member 22 and with it the shaft 20 to be rotationally displaced with respect to member 32 and shaft 18, also in the same direction as the arrow. Thus, it may be said that the governing means operates to advance shaft 20 with respect to the engine cycle upon increase in speed of operation of the engine and such advance, in accordance with the present invention, is employed to advance the period with respect to the engine cycle as the speed of the engine increases.

70 Engines of the kind to which the present device is particularly applicable may be operated to the best advantage with variation of the timing of ignition in accordance with engine speed, and the characteristics of the governing means

just described are such that it may in some instances be advantageous to vary the timing of the ignition simultaneously with the variation in the time of injection by means of the single governor.

5 To this end, the element controlling the time of ignition is advantageously driven from the driven side of the governor. In the embodiment illustrated in Fig. 1, wherein high tension spark ignition is shown, the shaft 68 for driving the ignition timing and distributing mechanism of conventional form indicated generally at 70 is driven by a suitable gear connection between shaft 68 and shaft 20.

10 As will be evident from the foregoing description, 15 the governing device is extremely rugged and simple in its construction, and has a minimum of frictionally moving parts which are readily enclosed and protected in a small and compact casing. It will further be evident that the governor 20 is readily adapted for effecting the desired amount of variation in timing for engines having different characteristics, merely by using loading springs of different strength which may readily be removed and replaced.

25 As will be seen from the construction shown on the drawing by way of example, the direction of the forces transmitted by the toothed gear is such that wearing is brought to minimum and efficiency to maximum. Also the mounting of 30 the weights attributes to the improvement, as the bolts on which the weights are rotatably fixed, are journaled on both their ends.

35 The invention is not to be considered as restricted to the specific form of device hereinbefore shown and described by way of example, but is to be considered as embracing all changes and modifications in the governor structure and in its manner of application which may fall within the scope of the appended claims.

40 What I claim is:

45 1. In apparatus of the character described, governing means for altering the angular relation between a rotary driving element and a rotary driven element in accordance with variations in speed of operation of the driving element comprising a cup shaped member adapted to be connected to one of said elements, said member having a hub portion and a rim portion and internal gear teeth on said rim portion, a second 50 member mounted on said hub portion and having relative rotational movement with respect thereto, said second member being adapted to be connected to the other of said elements, a pair of congruent centrifugal weights eccentrically mounted for pivotal movement on said second member, each of said weights having gear teeth meshing with said internal gear teeth to transmit drive from one to the other of said members and to produce angular displacement 55 between said members upon pivotal movement of the weights, and a pair of loading springs for said weights, said loading springs mutually interconnecting the weights at different distances from their respective pivot points, said springs being symmetrically arranged with respect to the axis of rotation of said members, and the opposite ends of each spring being respectively connected to the different weights at different distances from the pivot points thereof.

60 2. In apparatus of the character described, governing means for altering the angular relation between a rotary driving element and a rotary driven element in accordance with variations in speed of operation of the driving ele- 65

ment comprising a cup-shaped member adapted to be connected to one of said elements, said member having a rim portion and internal gear teeth on said rim portion, a second member mounted co-axially within said cup-shaped member and having relative rotational movement with respect thereto, said second member being adapted to be connected to the other of said elements, a pair of congruent centrifugal weights eccentrically mounted for pivotal movement on said second member, each of said weights having gear teeth meshing with said internal gear teeth to transmit drive from one to the other of said

members and to produce angular displacement between said members upon pivotal movement of the weights, and a pair of loading springs for said weights, said loading springs mutually interconnecting the weights at different distances from and on the opposite sides of their respective pivot points, said springs being symmetrically arranged with respect to the axis of rotation of said members and the opposite ends of each spring being respectively connected to the different weights at different distances from the pivot points thereof. 5
